UNITED STATES PATENT OFFICE.

WILLIAM A. SMITH, OF SHERMAN, TEXAS, ASSIGNOR OF ONE-HALF TO
ALLAN M. McBEE, OF SHERMAN, TEXAS.

DEVICE FOR PRESSING TROUSERS.

SPECIFICATION forming part of Letters Patent No. 784,187, dated March 7, 1905.

Application filed October 28, 1904. Serial No. 230,413.

To all whom it may concern:

Be it known that I, WILLIAM A. SMITH, a citizen of the United States, residing at Sherman, in the county of Grayson and State of Texas, have invented certain new and useful Improvements in Devices for Pressing Trousers; and I do declare the following to be a full, clear, and exact description of the invention, such as will enable others skilled in the art to 10 which it appertains to make and use the same.

My invention relates to improvements in devices for pressing clothing, more particularly trousers or pantaloons.

The object of my invention is to provide a 15 simple and efficient device of this character by means of which a pair of trousers may be pressed and creased, so that all bagginess and wrinkles will be removed from the same.

With the above and other objects in view the 20 invention consists of certain novel features of construction, combination, and arrangement of parts, as will be hereinafter more fully described, and particularly pointed out in the appended claims.

25 In the accompanying drawings, Figure 1 is a top plan view of a trousers-press constructed in accordance with my invention. Fig. 2 is a side elevation of the same. Fig. 3 is a longitudinal sectional view taken on the line 3 3 of Fig. 1. Figs. 4 and 5 are transverse sectional views taken, respectively, on the lines 4 4 and 5 5 in Fig. 1; and Fig. 6 is a detail sectional view taken on the line 6 6 in Fig. 1.

35 Referring to the drawings by numerals and letters, 1 denotes a base-board of suitable shape, and 2 a pressure-board, which is substantially the same shape as the base 1 and preferably composed of two half-sections 3 and 4, disposed longitudinally, as shown. Each of said half-sections consists of two parts 5 and 6, which are hingedly connected, as shown at 7. The parts 6 are comparatively short and are adapted to engage the lower portion or bottoms 40 of the legs of a pair of trousers T which is to be pressed between the boards 1 and 2. The parts 5 of said half-sections are comparatively long, so as to adapt them to engage the main portions of the legs of said trousers, and each

of them has at its upper and inner end a portion cut away, as shown at 8, to form a substantially V-shaped opening in the pressure-board 2, where the accumulation or goods and lining of the trousers may be gathered to permit the remaining portions to be properly 55 pressed, as hereinafter explained.

The means for clamping the sectional pressure-board 2 upon the trousers placed between it and the base-board 1, as here shown, consists in providing a series of concavo-convex 60 strips or blocks, which are adapted to be placed transversely upon the board 2 at suitable intervals, one being preferably used to clamp the parts 6 of the half-sections 3 and 4 and two or more being used to clamp the remaining parts 5 of said half-sections. By forming said blocks or strips 9 with a concave lower side the half-sections 3 and 4 will assume an angular position with respect to each other, so that the edges or creases in the 70 legs of the trousers will be properly pressed, the inner meeting edges of the half-sections 3 and 4 being disposed above the seams in the legs of the trousers, as shown. Each of the half-sections 3 and 4 of the pressure-board is 75 thus adapted to press one-half of the trousers-legs, and owing to the fact that said pressure-board is composed of these longitudinally-disposed half-sections the entire surface of the lower sides of the half-sections will firmly engage and press the trousers against the base-board 1. The strips or blocks 9 are held in position and the necessary pressure is exerted upon the board 2 by flat longitudinally-disposed springs 10, which are engaged with the upper convex sides of the transversely-disposed blocks or strips 9. Said springs 10 are preferably but not necessarily made of hickory or similar wood and have one of their ends pivotally connected by a loop or bail 11 to the 80 base 1 or to a cross-bar 12, secured upon the under side of the latter. The opposite ends of said springs are detachably connected, by means of pivoted bails 13, to the opposite ends of said cross-bars 12. It will be seen 85 that when it is desired to remove a pair of trousers from the press the bails 13 are swung outwardly and downwardly to disengage the

springs 10, and the latter and also the blocks 9 are then removed from the upper side of the pressure-board 2.

In placing a pair of trousers in the press their lower ends or bottoms are first clamped beneath the parts 6 of the half-sections 3 and 4 and, before the remaining parts 5 of said half-sections are clamped in position the upper portions of said trousers are stretched upon the base 1 and held in such position by a clamping means located at the upper end of the base, so that the sections 5 may be properly engaged with the main portions of the trousers-legs to permit the same to be thoroughly and neatly pressed. The said fastening or clamping means, as shown, comprises two clips 14, which are in the form of jaws 15, pivotally mounted, as at 16, upon the outer ends of bails 17, which are pivotally mounted, as at 18, upon the under side of the base 1. These jaws 15 are adapted to engage the front and rear edges or creases of the trousers T and are held in engagement therewith by a swinging transverse bar or rod 19. Said bar has one of its ends pivotally connected by a bail or loop 20 to one end of a spring 21, which is secured transversely upon the under side of the base 1. At the opposite end of said spring is a pivoted bail 22, which is adapted to be engaged by a swinging or pivoted catch 23, provided at one end of said bar 19. Said bar is thus detachably secured by means of the catch 23 and the bail 22, and it is held firmly in engagement with the clips 14 by means of said spring 21. The central portion of the under side of the bar or rod 19 is recessed, as shown at 24, at a point where the seams and bagginess of the upper portion of the trousers occur.

In order to dampen the trousers to more effectively press the same and form the usual creases therein, I attach along one edge of the base 1 a dampening cloth or sheet 26. Said cloth is similar in shape to the pressure-board 2 and is adapted to be placed between the two legs of the trousers, as clearly shown in Fig. 4 of the drawings. The connection of the cloth to the base may be effected in any desired manner; but I preferably form in one edge of the cloth a series of eyelets 27, which are detachably engaged with hooks or headed studs 28, provided in said edge of the base 1.

The operation and advantages of my invention will be readily understood from the foregoing description, taken in connection with the accompanying drawings. In placing a pair of trousers in the press they are first placed upon the base-board 1, and the dampening-cloth 26 is then inserted between the legs of said trousers. The half-sections 3 and 4 of the pressure-board are then placed in position and their lower parts 6 are clamped, as shown, upon the bottoms of the trousers. The parts 5 of said half-sections are then swung upwardly out of the way, while the up-

per portions of the trousers are stretched upon the base 1 and are clamped thereon by the clips 14 and the transverse clamping-bar 19. After the legs of the trousers have been stretched out smoothly the parts 5 of the half-sections 3 and 4 are then swung downwardly and secured in position, as shown in Fig. 4 of the drawings, by the strips 9 and spring 10.

While I have shown and described the preferred embodiment of my invention, it will be understood that various changes in the form, proportion, and the minor details of construction may be resorted to without departing from the principle or sacrificing any of the advantages of this invention.

Having thus described my invention, what I claim as new, and desire to secure by Letters Patent, is—

1. A trousers-press comprising a base, a presser-board having longitudinally-divided sections, blocks to bear on said sections and being hollowed on their inner sides to enable said sections to be disposed angularly with respect to each other, and means operative on said blocks to clamp said presser-board sections on the base.

2. A trousers-press comprising a base, a pressure-board divided longitudinally into two detached parts or sections, concavo-convex elements disposed transversely upon said pressure-board, springs upon said elements, and fastening means connecting said springs to said base to clamp said pressure-board upon said base, substantially as described.

3. A trousers-press comprising a base, a pressure-board divided longitudinally into two detached parts or sections, concavo-convex elements disposed transversely upon said pressure-board, springs upon said elements, longitudinally-extending springs upon said elements and detachable fastening means connecting the opposite ends of said springs to said base, substantially as described.

4. A trousers-press comprising a base, a pressure-board divided longitudinally into two detached parts or sections, concavo-convex elements disposed transversely upon said pressure-board, springs upon said elements, longitudinally-extending springs upon said elements having one of their ends pivotally connected to said base and detachable fasteners for securing the opposite ends of said springs to said base, substantially as described.

5. A trousers-press comprising a base, a pressure-board divided longitudinally into two half-sections, each of said sections being composed of hingedly-connected parts, means for securing one of said parts of each of said half-sections upon one end of said base to clamp the lower portions of a pair of trousers thereon, clips upon the opposite end of said base to engage the upper portion of a pair of trousers, a clamping device for said clips and the upper portion of a pair of trousers, said device comprising a transverse spring upon

said base, a swinging element connected to one end of said spring and adapted to engage said clips and the upper portions of a pair of trousers, and a detachable connection between the opposite ends of said spring and element, and means for clamping the remaining parts of said half-sections upon the intermediate portions of said base, substantially as described.

In testimony whereof I have hereunto set my hand in presence of two subscribing witnesses.

WILLIAM A. SMITH.
